CLAIM

We claim the ornamental design for a combined cash counter and printer, as shown and described.

DESCRIPTION

FIG. 1 is an elevated perspective view of a combined cash counter and printer in accordance with the present design. FIG. 2 is a rear view of the combined cash counter and printer shown in FIG. 1.

FIG. 3 is a right side view of the combined cash counter and printer shown in FIG. 1.

FIG. 4 is a left side view of the combined cash counter and printer shown in FIG. 1.

FIG. 5 is a front view of the combined cash counter and printer shown in FIG. 1.

FIG. 6 is a top view of the combined cash counter and printer shown in FIG. 1; and,

FIG. 7 is a bottom view of the combined cash counter and printer shown in FIG. 1.

Where the broken lines depict portions of the combined cash counter and printer that form no part of the claimed design.
